UNITED STATES PATENT OFFICE.

LEOPOLDO PIZZUTIELLO, OF NEW YORK, N. Y.

HAT-PIN.

1,009,339.

Specification of Letters Patent. Patented Nov. 21, 1911.

Application filed May 16, 1911. Serial No. 627,486.

To all whom it may concern:

Be it known that I, LEOPOLDO PIZZUTIELLO, a subject of the King of Italy, and a resident of New York, in the county of New York and State of New York, have invented certain new and useful Improvements in Hat-Pins, of which the following is a specification, taken in connection with the accompanying drawing, which forms a part 10 of the same.

This invention relates to hat pins and more particularly to one which will securely hold a hat on the head of the user, though permitting the ready withdrawal of the hat 15 pin when it is desired to remove the hat.

In the accompanying drawing showing an illustrative embodiment of my invention, and in which the same reference numerals refer to similar parts in the several figures,—

20 Figure 1 is a longitudinal vertical section through the hat pin showing the locking member in its operative position; Fig. 2 is a fragmentary vertical section illustrating the locking member in its inoperative position; 25 and Fig. 3 is a fragmentary plan view of a portion of the hat pin showing the head in section.

In the illustrative embodiment of my invention shown in the drawing, 1 is a hat pin formed of a hollow body member 2 having a point 3 which is preferably arranged at an angle to the body member. Within this body member I mount a locking member 4 having a point 5 which is adapted to 35 be forced through the opening 6 of the body member. This locking member 4 may be variously formed but I preferably form it from wire and bend one end to form an arm 7 by which the point 5 of the locking 40 member is either pulled into its inoperative position within the body member 2, Fig. 2, or is caused to pass through the opening 6 and assume its operative position, Fig. 1.

In use the body member 2 with the locking member 4 in its inoperative position, is forced through the hair of the user and after the hat and hat pin have been properly positioned, pressure upon the arm 7, in the direction of the point 3 of the hat pin, will cause 50 the locking member 4 to slide within the body member and force the point 5 through the opening 6 thereby providing the hat pin

with two points preferably arranged at an angle to each other. It is obvious that any pull upon the hat pin or upon the hat, will be resisted not only by the fixed point 3 of the hat pin but also by the removable point 5 which will practically insure the hat pin staying in its adjusted position on the head of the user.

I preferably, though not necessarily, bend the end 5 of the wire in the opposite direction from the point 3 so that when it is forced through the opening 6 it will assume substantially the position shown in Fig. 1. I also preferably provide the body member 2 at one end with a thimble 8 which may be secured to the body member in any manner but preferably by screw threads 9 formed on the interior surface of the thimble 70 and the exterior surface of the body member. This thimble is provided with a tapering slot 10 to receive the arm 7 of the locking member 4. It is obvious that the friction of the arm 7 upon the sides of the slot 10 will serve to frictionally hold the locking member in its operative position.

On the end of the thimble 8 I may secure, in any suitable manner, a head 11. This head may be glass, metal or any other suitable material, and may be given any suitable contour for purposes of ornamentation. By way of example I have shown the head spherical and provided with screw threads 12 to coöperate with threads 13 upon the end 85 of the thimble 8, the parts being screwed together until the head contacts with the shoulder 14 on the thimble.

The parts can be readily assembled by screwing the thimble 8 upon the body member, then inserting the locking member 4 within the body member 2 bringing the operating arm 7 into register with the slot 10. Upon then screwing the head 11 on the thimble the parts will all be locked together 95 and prevented from accidental displacement.

Having thus described this invention in connection with an illustrative embodiment thereof to the details of which I do not desire to be limited, what is claimed as new 100 and what it is desired to secure by Letters Patent is set forth in the appended claim:

The combination in a hat pin of a hollow body member provided with an opening

near its point, a movable locking member mounted within the body member and adapted to be extended through the opening and having an operating arm, a thimble 5 mounted on the end of the body member and provided with a tapering slot, the walls of which are adapted to frictionally hold the

arm in one of the positions to which it with the locking member is movable.

LEOPOLDO PIZZUTIELLO.
